CLAIM

The ornamental design for a flask, as shown and described.

DESCRIPTION

FIG. 1 is a perspective view of a flask showing my new design;

FIG. 2 is a front elevational view, with the rear elevational view being identical thereto;

FIG. 3 is a side elevational view with the side opposite thereto being identical thereto;

FIG. 4 is a top plan view thereof; and,

FIG. 5 is a bottom plan view thereof.

The broken line showing of the central region of the bottom surface is for environmental purposes only and forms no part of the claimed design.
